UNITED STATES PATENT OFFICE.

JOHN A. MACKENZIE, OF ALAMEDA, CALIFORNIA.

REINFORCED METALLIC LINING.

1,419,395.

Specification of Letters Patent. Patented June 13, 1922.

Application filed March 6, 1920. Serial No. 364,326.

To all whom it may concern:

Be it known that I, JOHN A. MACKENZIE, a citizen of the United States, residing in the city of Alameda, in the county of Alameda and State of California, have invented a new and useful Improvement in a Reinforced Metallic Lining, of which the following is a specification.

My invention relates to improvements in reinforced metallic linings wherein a metallic reticulum imbedded within a sheet of lead operates in conjunction with flanged washers arranged at regular intervals within the interstices of said reticulum to detachably retain said lining against a surface.

The present state of the art discloses a metallic lining permanently attached to the interior surfaces of evaporators and containers for the production of acids and the like, said lining being held to such surface by means of a metallic reticulum permanently attached to said surface by means of rivets or other permanent devices, said lining being flowed or cast, while in a fluid or melted state, through the interstices of the reticulum thereby requiring that such lining be applied to the container while in course of construction and within a shop having facilities for such application.

Some containers are too large to be constructed within the shop and in such cases the material of said container is shipped to the required location and there assembled. To line such containers with the means disclosed in the present state of the art would require the erection of a shop and transportation of suitable mechanism to make such applications.

The primary object of the present invention is to provide an improved reinforced metallic lining of the character described adapted for erection or application in the field or remote from the shop.

A further object of the present invention is to provide improved means for detachably securing the lining to a surface whereby said lining may be detached after the container has outlived its usefulness and reapplied to another container or the like.

A still further object of the invention is to provide an improved lining of the type set forth wherein the supporting reticulum may be more centrally imbedded within the lining to more efficiently support the weight thereof, and thereby provide superior en-

gagement and to increase facilities for preventing creeping or detachment of the lining.

A further object is to provide improved means for positioning the apertures in the bonding element to register with apertures in the rigid surface to which the lining is to be applied.

A still further object of the present invention is to provide improved means for lining containers and the like without the expensive process of previously tinning the surface or plate to which it is to be attached.

I accomplish these and other objects by means of the improved device disclosed in the drawings forming a part of the present specification wherein like characters of reference are used to designate similar parts throughout the said specification and drawings, and in which—

Fig. 1 is broken elevation of my improved lining partly broken away to disclose the supporting reticulum and the bonding means for securing the same to a surface;

Fig. 2 is a broken view of a section of the reticulum and the bonding means;

Fig. 3 is a sectional view taken on line 3—3 of Fig. 2 in the direction indicated;

Fig. 4 is a sectional view of the lining as applied to a metal plate;

Fig. 5 is an enlarged elevation of a modified form of bonding washer; and

Fig. 6 is a sectional view of Fig. 5.

Referring to the drawings the numeral 1 is used to designate a sheet of lead or other suitable metal impervious to the action of acids and having regularly spaced apertures 2 therein, within which is imbedded a metallic reticulum 3 having certain interstices registering or aligned with said apertures 2 of the sheet of lead 1.

Within such registering or aligned interstices of said reticulum 3 are the bonding means or washers 4 having a flange 6 around the edges of one side thereof.

The flanged side of the washers 4 are imbedded within the sheet of lead 1 while the opposite side of said washers 4 are arranged flush with the side of said sheet 1 thereby providing a bonding means adapted to be rigidly and detachably secured to a surface without pressure upon said lining.

The washers 4 are also provided with centrally disposed countersunk apertures 7 through which are inserted rivets 8 or other

suitable securing means, to secure said washers 4 and the lining to a metal plate 9, as disclosed in Fig. 4 of the drawings.

The flanges 6 of the washers 4 are arranged to engage the side of the reticulum 3 opposite the flush side of the said washers 4 by means of which novel arrangement said reticulum is securely and rigidly supported and retained, without distortion, owing to pressure, on said lining.

In operation the lining consisting of the sheet of lead 1, reticulum 3 and washers 4 are fabricated in the shop and transported to the field of operations. The lining is placed in position so that the apertures 7 of the washers 4 register with the apertures 11 in the plate 9 to be covered or lined and the rivets 8 are then passed through the registering apertures 7 of the washers 4 and the apertures 11 of the plate 9 and suitably secured.

As the washers are provided at regular intervals within the interstices of the reticulum 3 it is obvious that a uniform adherence will be provided to effectively and efficiently retain the lining to the metal plate 9.

It sometimes happens that the lining is slightly distorted during transportation thereby throwing the apertures 7 of the washers 4 out of alignment with the apertures 11 of the plate 9. In order to properly reposition the apertures 7 I have provided the modified form of washer 4' having concentric nested washers 12 and 14 rotatably mounted therein.

By means of this novel arrangement the apertures 7 may be repositioned to align or register with the apertures 11 in the plate 9.

The washers 4' are also provided with the same flanges 6 in order to effectively engage the inner side of the reticulum 3.

After the rivets 8 have been properly secured the apertures 2 in the sheet of lead 1 are filled with lead discs 16 and the adjacent edges of said disc 16 and the apertures 2 are melted and fused by the application of heat in such a manner as to fully cover the rivet heads and thereby prevent exposure of same to the action of any acids which may come in contact with the lining.

The junction of the sections of the linings are filled with a strip of lead 17 to which heat is also applied to fuse the adjoining edges of adjacent plates, thereby effectively combining the several sections to form a unit and effectively line the entire structure.

It is obvious from the foregoing that I have provided an improved reenforced lining having improved means for effectively supporting the same to the surface of a container or the like, whereby said plates may be removed when the container or plate to

which they have been applied is no longer useful.

It is also obvious that I have provided an improved metallic lining adapted to be applied in the field where the containers are too large to be constructed within the shop and later transported to the desired location.

Having thus described my invention what I claim as new and desire to secure by Letters Patent is—

1. A reenforced metallic lining comprising a sheet of lead; a metallic reticulum imbedded within the lead; and washers mounted within the interstices of the reticulum and within the lead end flush with one side thereof to detachably connect said reticulum and lead to a surface.

2. A reenforced metallic lining comprising a sheet of lead; a metallic reticulum imbedded within the lead; and flanged washers mounted at regular intervals within the interstices of the reticulum and having one side thereof arranged flush with one side of the sheet of lead whereby said lining may be detachably connected to a surface, said flanges on the washer engaging the reticulum to hold the same and the lead rigidly against said surface.

3. A reenforced metallic lining comprising a sheet of lead; a metallic reticulum imbedded within the lead; and apertured flanged washers mounted at regular intervals within the interstices of the reticulum and having one side thereof arranged flush with one side of said sheet of lead, said flanges operating to engage the reticulum and hold the same and the lead against a surface; and means for engaging the apertures within said washers and for retaining said washers and the reticulum and sheet of lead against a surface.

4. A reenforced metallic lining comprising an apertured sheet of lead; a metallic reticulum imbedded within the sheet of lead and having certain interstices registering with the apertures in said sheet; apertured flanged washers mounted within such registering interstices of the reticulum and having one side thereof arranged flush with one side of the sheet of lead and the flanges engaging the far side of the reticulum imbedded therein; and means for engaging the apertures within the washers and for holding the flush sides thereof against a surface to which the lining is to be attached whereby said flanges on said washers may engage and retain the reticulum and sheet of lead against such surface.

In witness whereof I hereunto set my signature.

JOHN A. MACKENZIE.
